APPARATUS FOR PNEUMATICALLY SEPARATING RELATIVELY MOIST COMMINUTED MATERIAL

Jesse M. McGee, Oak Park, Ill., assignor to Roberts and Schaefer Company, Chicago, Ill., a corporation of Illinois

Application February 16, 1945, Serial No. 578,201

2 Claims. (Cl. 209—3)

1

This invention relates to the art of separating materials, and is particularly concerned with a new process and apparatus for separating relatively moist comminuted material in accordance with the specific gravities of its particles.

The invention is especially adapted to and will be described herein in connection with the dry cleaning or separation of raw coal containing a relatively large amount of fines and carrying an amount of excess surface moisture that would normally cause difficulties in dry cleaning or might even prohibit the economical and efficient use of dry cleaning equipment.

Coal of such character, which now represents for the industry a problem of considerable magnitude, is produced in relatively large quantities, e. g., by modern mining methods including those which require water spraying at the face, and also due to the growing necessity of mining relatively poor deposits. The amount of fines in such coal is too large for economical wet cleaning, e. g., by float-sink methods, and the excessive moisture content stands in the way of efficiently employing pneumatic or dry cleaning apparatus. The troublesome aspects become manifest with materials having a particle size of approximately $\frac{1}{2}''$ x 0" and containing excess surface moisture about 1% to 3% above normal.

The difficulties which must be considered will be apparent from the following brief discussion of the principal conditions that arise in the dry cleaning of coal containing relatively large amounts of fines:

1. Particles which are smaller than 48 mesh are troublesome and impede efficient dry cleaning, even in the absence of excess surface moisture. This is pointed out in detail in my Patent 2,350,625, issued June 6, 1944. The troubles with such material may be overcome, as proposed in this prior patent, by removing the fines of critical particle size and subjecting the remaining coarser material to dry cleaning.

2. Excess surface moisture of about 1% to 3% above normal contained in the raw material introduces difficulties in the removal of the undesirable fines, and causes trouble in the dry cleaner even in the absence of such critical fines, due to the tendency of the small particles to lump, consequently causing fouling, packing and clogging of the material bed.

This invention proposes to overcome these and other drawbacks by removing from the raw material, preparatory to dry cleaning, fines which are smaller than 48 mesh, in the presence of a heated air stream, and subjecting the remaining material

2

of coarser particle size to dry cleaning, in the presence of a heated air stream which is circulated through the dry cleaner in a closed circuit.

Either one of the principal procedures noted in the preceding paragraph may be applied independently of the other. That is to say, the raw material may be subjected to the action of a heated air stream for the purpose of facilitating the removal of fines of predetermined size preparatory to pneumatic separation, and the separation may be carried out in the usual way; and, alternatively, the preparatory treatment of the raw material may be carried out without the use of a heated air stream or may be omitted if desired, and the operation of the dry or pneumatic cleaner may be facilitated by circulating a heated air stream therethrough in a closed circuit. The features may also be combined as stated before.

20 Other objects of the invention are concerned with humidity and temperature control of the air stream circulating through the system.

The various objects and features are described below in detail with reference to the accompanying drawing, showing in diagrammatic form an organization of apparatus for use in carrying out the invention.

Referring now to the drawing, numeral 1 indicates a feed or storage bin from which the relatively moist raw coal is fed by suitable means, e. g., a conveyor 2 to the feed conduit comprising the surge bin 3. The latter in turn feeds the raw material to the mechanical air separator 4 which may be of the general type disclosed in U. S. Patent No. 1,783,357, dated December 2, 1930.

The mechanical air separator 4 receives the material from the surge bin through the connecting conduit 11. The separator comprises an outer shell which is cylindrical at the top and of inverted conical shape in its bottom portion. The outer shell contains an inner conical shell, a revolving distributor plate for receiving the raw material, and a fan for creating a circulating air current. The raw material within the separator is projected laterally by centrifugal force from the distributor plate across the path of rising air currents created by the fan which picks up and carries away in suspension only the finer particles, whereas the heavier particles 50 gravitate out of the air stream into the inner conical shell or interior cone.

The operation of the mechanical air separator 4 is facilitated, and troubles which may otherwise result from the excess moisture content of the raw material are eliminated by cir-

culating through the separator 4 a heated air current of controlled temperature and humidity.

The invention provides for this purpose a heater indicated at 5 which may be a furnace or other suitable equipment. Fresh air is supplied to the heater at 6, and heated air is conducted to the air separator 4 through suitable conduits which may be heat-insulated if desired or necessary, and which include the branches 7-8-9-10. Conduits 7, 8 and 9 are part of the heated air supply circuit taking care of the mechanical air separator 4 as well as of the dry or pneumatic cleaner 16, while the conduit branches 10 and 10a shown in dot-dash lines are provided specifically for supplying heated air to the raw material on its way through the feed conduit 3 and connecting conduit 11 to the air separator 4. Valves may be included in the branch lines 10 and 10a at any suitable or desired point. As shown in the drawing, the conduit 10 may terminate in the neck or connecting conduit 11, or it may terminate, as indicated at 10a, in the upper part of the surge bin or feed conduit 3. In either case, the heated air is supplied to the relatively moist raw material about to enter the air separator and effects partial drying of the coal. The heated air is thus supplied to the air separator 4 together with the raw material.

The heavier and coarser particles (in this case $\frac{1}{2}$ " to 48 mesh) emerge from the mechanical air separator 4 laterally at an angle through the conduit intermediate 12 for separation in the air controlled gravity separator or dry cleaner 16. The fines, that is, in this specific embodiment, particles of a size smaller than 48 mesh, emerge for disposal from the mechanical air separator 4 centrally at the bottom through a valve 13 positioned in the discharge conduit and are disposed along the line 14. The valve 13 may be a double flap valve forming an air lock. The two flaps form in the discharge conduit an intermediate chamber which alternately fills and empties, thus permitting discharge of the fines while preventing escape of substantial amounts of air.

The pneumatic gravity separator or dry cleaner 16 may be of the type shown in Patent 2,245,942, dated June 17, 1941. The description of some of its salient features is included in the explanations which follow.

The separator 16 is provided with a bottom air chamber and with a perforated trough-like inclined deck for receiving the raw feed from the intermediate conduit 12 for stratification and separation in accordance with the specific gravities of its particles.

The conduit 38 shown in dot-dash lines and including the valve 40 bleeds air from the intermediate conduit 12 to mix with the exhaust air from the separator 16 flowing through the exhaust conduit 19. Residual fines carried with the air in the intermediate conduit 12 are thus shunted away from the separator 16. The air in conduit 12 is chilled and has taken up moisture on its way through the air separator 4, and being bled off through conduit 38, cannot adversely affect the operation of the separator 16.

Air impulses are injected into the air chamber of the separator 16 by means of a fan 17. The air injected is clean and dry air maintained at about 350° F. The impulses go through the perforated deck and through the layer of material thereon, which moves along the deck, keeping the material bed mobile and causing stratifica-

tion of its particles in accordance with the specific gravities thereof. The clean coal is discharged at the opposite end of the separator as indicated by the arrow marked "Clean coal."

- 5 The refuse, that is, particles of heavier specific gravities and middlings consisting of particles of intermediate specific gravities, may be discharged from the separator 16 along the lines marked "Refuse" and "Middlings," respectively.
- 10 The previously noted patent may be consulted for further details concerning the structure and operation of the separator 16.

The separator 16 is provided with a dust hood 18 which conducts the dustladen exhaust air into the conduit 19, provided with a suitable valve 20, and thence into a so-called cyclone collector 21. The valve 20 may be part of the intake conduit of the cyclone collector. The air injected into the cyclone collector carries residual fines from the conduit 38 and fines produced by attrition in the separator 16. It also carries a certain amount of moisture taken up from the material.

The cyclone collector may be of the general type described in U. S. Patent No. 1,985,947, dated January 1, 1935. Its shape, as indicated in the drawing, is exteriorly somewhat similar to that of the mechanical air separator 4. The internal mechanism is, however, somewhat different. The collector is provided in its upper part with a cylindrical interiorly downwardly depending extension forming in the upper cylindrical portion an annular channel. The dustladen air from the conduit 19 is injected into the collector tangentially so as to create a rotating air stream which gyrates downwardly along the inner walls thereof. The efficiency of the collector is a function of the inlet velocity and the fineness and character of the particles to be separated from the dustladen air coming from the separator 16, and it will be apparent that the inlet velocity can be effectively regulated by properly positioning the inlet valve 20. The entering dustladen air stream is directed tangentially along the inner surface of the outer wall of the collector so that the maximum whirling or centrifugal effect is imparted to the suspended material which is deposited or concentrated adjacent the inner closed walls of the collector housing. The smaller lower end of the housing may be equipped with an upwardly and inwardly projecting conical bottom, as described in detail in the previously mentioned patent, and is provided with an outlet leading substantially tangentially from one side of the housing to connect with the outlet conduit indicated at 22. This outlet or exhaust conduit discharges the fines concentrated in the collector 21 through a valve 23, which may be of the double flap air lock type described in connection with discharge valve 13 of the air separator 4. Therefore, substantially only the concentrated exhaust fines are discharged through valve 23 and conduit 22.

The above described operation of the cyclone collector, details of which may be had from consulting the previously mentioned Patent 1,985,947, is improved in the present case by recirculating a certain amount, say 10%, of the material fed into the collector. This is done through the conduit 24 shown in dotted lines by a suitable fan or blower 25. A valve 26 may be included in conduit 24, for the purpose of regulating the amount of material for recirculation.

The air escaping from the collector 21 through the conduit 26 is substantially clean air which is free of fines and dust particles. This clean air is conducted through conduits 27 and 28, which

may be heat-insulated, if desired or necessary, back to the blower or fan 17.

There is thus provided a closed circuit for circulating air through the pneumatic separator 16 which is in general in accordance with the disclosure in my previously mentioned Patent 2,350,625. The mere circulation of air in the closed circuit, through the separator, however, is insufficient in the presence of raw material containing a substantial amount of fines and excess surface moisture. In order to take care of this condition, I have provided means for heating the circulating air and for conducting it through the separator in a closed circuit in such a manner that the temperature of the air injected into the separator will always be substantially 350° F. and its humidity a predetermined minimum.

The heating means includes the previously mentioned heater 5 and the conduits 7 and 8 which connect with the return conduit 28. A temperature control device, for example, a thermocouple 30, is provided just ahead of the fan 17. The thermocouple governs the operation of the valve control device 31 which in turn is adapted to operate the valve 32 in the auxiliary air supply conduit 33 which connects with the conduits 7-8 coming from the heater 5. If the temperature just ahead of the fan 17 exceeds the maximum desired temperature of 350° F., the thermocouple will cause operation of the valve control device 31 which then opens the valve 32 so as to admit into conduit 33 atmospheric air until such time when the temperature is reduced to the desired 350° F. On the other hand, if the temperature is just right or if it should drop slightly below 350° F., the valve control device 31 will react under the control of the thermocouple 30 to close the valve 32 so as to inhibit inlet of atmospheric air into the system.

Numeral 35 indicates a moisture control device which may be of any suitable, desired and approved type, including a recorder or wet and dry bulb type adapted to indicate to the operator the humidity of the circulating air coming from the cyclone collector 21. The humidity of the air coming from the collector should be maintained below the dew point. A vent fan 36 connected with the conduit 28 through a valve 37 is provided for this purpose and allows the operator to regulate the humidity of the air as desired. If the humidity of the circulating air is too high, the operator will open the valve 37 and exhaust air from the closed circuit, which is then replaced by dry heated air from the heater 5 until the desired humidity is restored.

The operation of the system will be apparent from the above description, but may be summarized as follows:

Raw material containing a relatively large amount of fines and excess surface moisture above 1% to 3% of normal is first subjected to the drying action of heated air tapped off from the conduit 28 through the branch pipes or conduits 10. The raw material is then dropped into the mechanical air separator 4 together with the heated air. The separator effects removal of most of the critical fines, that is, particles smaller than -48 and feeds the remainder of the material, consisting of coarser particles, to the pneumatic separator 16. The operation of this separator is facilitated by the current of heated air of controlled temperature and controlled humidity which circulates in a closed circuit from the fan or blower 17 through the separator, dust collector,

and back to the fan 17. The humidity of the circulating air and the temperature thereof are under constant control, the temperature being kept substantially about 350° F. and the humidity below the dew point. In other words, dry, heated air is circulated through the separator 16. The temperature control is automatic by means of a thermocouple 30 which governs the operation of the valve control device 31 and the latter in turn governs the operation of the valve 32 controlling the amount of atmospheric air to be introduced into the closed circuit at any one time for the purpose of temperature correction. The moisture control may likewise be automatic by providing suitable operating means for the valve 37 under the control of the humidity measuring device 35. The exhaust air from the separator 16 is subjected in this closed circuit to the operation of the cyclone collector 21 which collects and concentrates the residual fines and dust contained in it. The circulating air is thus automatically purified, and clean air of a controlled temperature and humidity is returned to the pneumatic separator.

The invention contributes toward the solution of the difficult problem of cleaning relatively moist material, particularly material containing relatively large amounts of fines, and using therefor in an efficient manner dry cleaning apparatus which heretofore was considered unsuitable for the purpose. As a matter of fact, it is believed that the invention actually constitutes a solution for this important problem.

It is understood, of course, that the invention is not limited to the cleaning of coal, but may likewise be used in connection with the separation of materials exhibiting different properties but posing similar problems.

Changes may be made within the scope and spirit of the appended claims which define what is believed to be new and desired to have protected by Letters Patent of the United States.

I claim:

1. Apparatus for pneumatically separating raw coal containing a relatively large amount of fines and a substantial amount of surface moisture comprising a feed conduit for conveying a stream of such raw coal, means for injecting into said feed conduit heated air at a temperature of about 350° F. to abstract moisture from the raw coal moving therethrough, a connecting conduit for receiving the stream of raw coal from said feed conduit together with the heated air injected thereto, an air separator for receiving said raw coal stream from said connecting conduit together with the air therein and for removing from such coal stream fines which are smaller than about 48 mesh, an intermediate conduit for receiving from said air separator the remaining coarser raw coal particles together with the air introduced into said air separator with the raw coal from said connecting conduit, means for withdrawing the air from said intermediate conduit together with residual fines contained in the stream of material of coarser particle size moving therethrough, and a pneumatic separator for receiving the raw coal of coarser particle size from said intermediate conduit and for separating such raw coal in accordance with the specific gravities of the particles thereof.

2. The structure and combination defined in claim 1, together with means for withdrawing from said pneumatic separator air together with residual fines and discharging such residual fines

the fines together with removed with the air from said intermediate conduit.

JESSE M. McGEE.
